UNITED STATES PATENT OFFICE.

HUBERT JOSEPH DEBAUCHE, OF GILLY, BELGIUM.

BRAKE-GEAR FOR WINDING MACHINERY.

No. 900,671.

Specification of Letters Patent.

Patented Oct. 6, 1908.

Application filed April 28, 1908. Serial No. 429,666.

To all whom it may concern:

Be it known that I, HUBERT JOSEPH DEBAUCHE, a subject of the King of the Belgians, residing at Gilly, in the Kingdom of Belgium, have invented new and useful Improvements in Brake-Gear for Winding Machinery, of which the following is a specification.

In winding machinery the question of brake gear arranged to stop the winding cages has always presented the greatest interest by reason of the grave and relatively frequent accidents caused by the absence of safety gear which will afford the desirable guarantees. This interest is increased in proportion to the increase of depth of the pit shafts which involves the high speed of winding and thus increases the danger of operation of the cages.

Generally winding machinery is furnished with the following safety apparatus:

(A) A main power device of such power that the unwinding of the gear is impossible even if steam is operating on the piston.

(B) This power device is put into action by hand by the driver or automatically.

(C) A mechanism called "a prevention device" putting the main power device into action automatically if the cage passes a certain height above the pit mouth level.

Experience has shown many times the non-
efficiency and even danger of these devices. In effect the putting in action of the main power device upon a winding gear operated

at high speed has always involved grave danger either to the machinery or to other parts of the installation. Further when the cage traverses the pit mouth at a great speed, as it passes the critical space (consisting of

the intermediate space which it ought not to pass between the pit mouth and the winding pulleys above) in a very short time, *i. e.* in a small fraction of a second the accident occurs before the mechanism of the said

"prevention device" has been able to put the main power device into action. In other words the time necessary for the "prevention device" to put the main power device into action is greater than the time taken by

the cage to traverse the critical space if it is operated at a great speed.

It follows from the preceding that the devices A and B are only able to operate suitably if the rising cage passes the surface of the pit mouth with a very small velocity, *i. e.* when the danger is *nil*, or nearly so. In

consequence it is indispensable that each winding machine independently of the devices A and B indicated above be furnished with a device which may be called "a light power device" adapted to fulfil the following conditions:

1. To be put instantaneously into action upon a winding engine which turns at its greatest velocity in developing its maximum work and to stop it in a relatively short time and without causing any damage.

2. To be variable, *i. e.* that it may go on increasing from the starting in action up to the stoppage of the machine. At this moment the power should be such that the machine cannot be moved under the action of the cages.

3. To be put into action by hand by the driver irrespective of the position of the cages in the shaft. To be controlled by the same lever as the main power device, *i. e.* by virtue of the simple hand lever the driver should be able to actuate either the "light power device" only or the two power devices together.

4. To operate automatically in the dangerous zone of the shaft. The length of the dangerous zone is such that if it is supposed that the "light power device" commences to operate upon the apparatus moving at its maximum velocity when the rising cage enters this zone, the machine may be completely stopped before the rising cage reaches the surface of the pit mouth.

5. At the moment of passage of the rising cage into the dangerous zone to continuously control the velocity of the apparatus up to the arrival of the cage at the pit mouth, and if the slowing of the apparatus is not such as to insure the arrival of the cage at the surface with a velocity equal or less than the very small velocity assigned to it that avoids danger, then to automatically come into action and stop the apparatus.

6. To be capable of operating at all times as well as for the time the rising cage is in the dangerous zone, *i. e.* the brake will stop the machine as many times as the driver deviates from the prescribed speed.

7. The apparatus having been stopped and being immovable under the action of the "light power device" the mechanism of this latter to be capable of being freed and ready to act afresh and instantaneously so as to allow the driver to continue the ascension.

8. At the commencement of a descent the

apparatus may attain very rapidly its regular velocity which is so much the better for the good utilization of the steam without the apparatus of the "light power device" injuring the working of the apparatus.

The brake mechanisms in the drawings completely satisfy all these requirements, and they are represented as applied to a pendulum brake, but it follows that they can 10 be applied on the brake in a pit or any other brake space.

In the drawings, Figure 1 represents a side elevation of the principal parts of the hoisting apparatus and controlling means 15 therefore, parts being in section; Fig. 2 is a transverse sectional view of the auxiliary steam cylinder and its valves; Fig. 3 is a like view of the main power device on the broken line 3—3 of Fig. 4, including a sectional 20 view of one of the valves of the auxiliary cylinder; Fig. 4 is a general plan view of the device illustrated in Fig. 1, the steam cylinders being in section, and Fig. 5 is an enlarged detail of the variable automatic stop 25 mechanism to be hereinafter described.

Throughout the following detail description and on the several figures of the drawings similar parts are referred to by like reference characters.

30 The mechanism disclosed comprises:

(1) A balance lever A upon which act two pistons C and E.

(2) A brake cylinder B in which operates piston C. The rod C¹ of this latter is fixed 35 to the balance lever A in such manner that this latter will be lowered when the piston C descends, while the balance lever can descend without drawing with it the piston C. On the piston rod C¹ is suspended a counterweight F. The cylinder B, the piston C and the counterweight F constitute the main power device.

(3) A "light brake cylinder" D in which operates a piston E of which the rod E¹ is connected directly in its vertical movement 45 with the balance lever A, and this latter cannot move vertically without drawing with it the piston E and inversely. The cylinder D is furnished with two valve boxes arranged in series (Fig. 2) in such manner that the steam arriving by the orifice D¹ passes the first valve box to enter the second by the orifice D¹¹. The valve boxes are furnished each with a valve of which one the valve G is 55 controlled by the driver's hand and the other the valve H receives its motion from an automatic mechanism independent of the driver.

(4) An axle I controlled by the driver's 60 lever either directly or by a system of levers and rods. On this axle is fixed a bell crank lever J of which one of the two arms controls by means of a vertical rod J¹ the valve K of the cylinder B (Fig. 3) and of which 65 the other arm controls by means of a hori-

zontal rod J¹¹ another bell crank lever L. This latter engages in its turn by means of a vertical rod L¹ the valve G of which it is a part (Fig. 2).

Upon the axle M is mounted a loose lever N having three arms of which the horizontal arm controls by means of a vertical rod N¹ the valve H (Fig. 2). The lower arm controls the throttle valve O disposed in the main steam pipe between the regulator of 70 the engine and the boilers. The upper arm of N receives its movement from a counterbalance P by the intermediation of the levers R, Q and rod Q¹. The axle S on which is 75 fixed the levers R, Q is disposed in such a way as to be controlled by a special lever within reach of the driver.

The counterbalance P is held suspended by means of a rod T of which the guided upper end is movable vertically and is 80 adapted to hang itself on to a knuckle lever U oscillating about a fixed point X (Figs. 1 and 5). The knuckle lever U is influenced in the first place by a rod V pivoted to a fixed point W and furnished with a balancing spring which forcibly maintains the said knuckle lever in contact with the rod T in order that the vibrations of the machine may not in any case produce an untimely unhooking of the rod T and the fall of the counterweight P. It is evident that the rod V can be replaced by any spring or a counterweight acting on the knuckle lever for maintaining the hooking action of the rod T. The knuckle lever U is also influenced by the 85 rods Z and Y pivoted respectively at the ends of two small free levers a and b oscillating about the axes c and d. On the axes c and d oscillate two other free levers e and f each furnished with a counterweight e¹ and f¹, the 90 object of these counterweights being to always bring back the levers e and f into a nearly vertical position. The counterweight arm of the lever e is provided with a tappet 95 adapted to contact with the lever a and cause the lever a to rotate positively with the lever e in a rotation set up from the right towards the left about the center c. Consequently if for any reason the lever e moves from the right to the left it engages in its movement 100 the lever a which in turn will operate the knuckle lever U by the intermediation of the rod Z and will thus effect the unhooking of the rod T and consequently the fall of the counterweight P. On the contrary if the 105 lever e is moved from left to right, it separates itself from the lever a inclining itself towards the right and will thereafter retake its quasi vertical position under the action of 110 its counterweight when the force which moved it shall have ceased to act. Similarly the lever f will operate the lever b in its oscillatory movement from left to right and it oscillates independent of the lever b from 115 right to left.

The axes *c* and *d* are carried by the bent levers *g* and *h* oscillating respectively about fixed points *i* and *j* while the other arms of the two bent levers are pivoted on the same rod *k* which receives its motion from the governor *l*.

When the governor *l* is in its lower position (that shown in Fig. 1) the two levers *e* and *f* occupy the lower position indicated in Figs. 1 and 5 but it is at once seen that if the governor *l* rises and travels towards its upper position, the bent levers *g* and *h* oscillating about the fixed points *i* and *j* under the action of the said governor, the levers *e* and *f* will be raised bodily very nearly vertical and will reach a higher position than that indicated on the drawing and corresponding to the upper position of the governor *l*. Further a screwed spindle *m* connected with the main shaft by means of a series of gear wheels operates a nut *n* in one direction or the other according to the rotation of the apparatus. This nut is provided with two inclined parts *o* and *p* each composed of a series of small steps; the vertical faces of the steps of the part *o* are adapted to engage against the end of the lever *e* on the nut being moved from right to left, and it is easily understood that if the governor is in the upper position it is the upper step *q* which engages the end of the lever *e* while if the governor *l* occupies the lower position, it is the step *r* which engages the lever *e*.

The lever *e* being engaged by any one of the steps of the part *o* will oscillate from right to left and will operate the lever *a* in the opposite direction and will bring about thus the unhooking of the rod *T* and the fall of the counterweight. When the nut *n* moves from left to right the vertical faces of the steps of the part *p* will act in a similar manner on the end of the lever *f*.

Method of Operation of the Light Power Device.

45 *A. By hand.*—Supposing that the driver operates the lever *I'* on the axle *I* and brings it to the middle position the valve *K* (Fig. 3) is moved from the upper toward the lower position but without covering up the lower port bringing the steam under the piston. It follows that as regards the main power device nothing is changed and the piston *C* and the counterweight *F* continue to occupy their upper positions corresponding to that of the released power device. At the same time the valve *G* (Fig. 2) is also moved from above towards the bottom but its travel is calculated so that for the half travel of the driver's lever the valve *G* covers the lower port communicating with the under side of the piston thus putting this latter in communication with the atmosphere; at the same time the said valve *G* uncovers the upper port admitting steam to

the upper side of the piston *E*. In consequence of this the balance lever *A* not being retained by the steam pressure under the piston *E* falls sharply sliding upon the piston rod *C'* and tightens the light power device; 70 as the upper port admitting the steam above the piston *E* is relatively small, the steam not instantaneously filling the volume produced by the descending piston *E* at boiler pressure it follows that the tightening of the 75 light power device is only made at the outset under the action of the dead weight of the balance lever *A* and the piston *E* with its rod *E'*. The steam flowing through the upper port in the space above the piston *E* the 80 force of the brake increases until the steam pressure in the space becomes stationary. At this moment the force of the light power device attains its maximum. Assuming now that the driver again takes the hand 85 lever which is in the half stroke position and pushes it onward to the point opposite the original position, immediately the valve *K* covers up the lower port and the steam which is under the piston *C* is put into communication with the atmosphere. It follows that the piston *C* drawn by the counterweight *F* descends and rests its weight in its turn upon the balance lever *A* by means of a shoulder on the piston rod *C'* (Fig. 1). 90 The main power device is then also applied. If the driver draws his lever back to the starting point, the two valves *G* and *K* are put into the positions indicated in the drawings (Figs. 2 and 3) and the steam is reintroduced under the pistons *C* and *E*, 100 hence the two power devices will be released.

It will be seen from the foregoing that owing to the mode of attachment of the piston rods *C'* and *E'* on the balance lever *A* 105 and to the mechanism shown in the drawing, it is possible to operate by means of a single hand lever:—(a) The light power device only. (b) The light power device and the main power device simultaneously, both acting on the same brake pulley by the same weights and the same balance lever.

110 *B. Automatic light power device.*—Assume that the rising cage enters the dangerous zone of the shaft with a speed corresponding to the maximum speed of the apparatus. At this moment the governor *l* will occupy as above seen its upper position and consequently the two vertical levers *e* and *f* will occupy their upper position. It 115 will be assumed that the nut *n* is moved from right to left on the shaft *m* and is placed in the position indicated in the drawing. If the driver does not slacken the speed of the machine it will be seen that the step *q* will come inevitably into contact with the end of the lever *e* and moving the lever *e* from right to left will effect the unhooking of the rod *Z* acting on the knuckle lever *U*. The rod *T* being unhooked falls sharply un- 125 130

der the action of the counterweight P (or of the spring in place thereof,) and the fall of this counterweight, by reason of the levers R, Q, N, and the rods shown in the drawing 5 immediately effects: (a) The closure of the throttle valve O, and complete cutting off of the steam from the motor cylinders of the machine. (b) The movement of the valve H from above to below (Fig. 2).
 10 The valve H in descending re-covers the lower port, and puts the under side of the piston in communication with the atmosphere, and further, it un-covers the upper port, admitting steam from the boiler direct 15 to the top of the piston E. In consequence, the balance lever A, no longer being retained by the pressure of steam under the piston E, falls sharply sliding the length of the piston rod C' and tightening the light brake; as 20 the upper port bringing the steam to the top of the piston is relatively small, the steam does not instantaneously fill the cylinder D, and it follows that the applying of the light power device is only effected at the beginning 25 under the action of the dead weight of the balance lever A and of the piston E with its rod. The steam flowing through the upper port into the space above the piston E, the force of the brake increases until the 30 pressure of the steam in this space becomes stationary. At this moment the power of the light power device has attained its maximum. This maximum power of the light power device can be regulated at will in the 35 following manner:—In the part of the cylinder D above the piston is arranged a passage v of sufficiently large diameter which communicates by means of a pipe with a cock w close to the driver and from which the steam 40 can escape into the atmosphere. It is easily understood that if this cock is completely open a minimum pressure as low as may be desired can be obtained above the piston E. Further, by closing the cock w more or less, 45 it will be possible to use all steam pressures between the minimum pressure as described above and boiler pressure. As the force of the light power device is proportionate to the steam pressure which exists above the 50 piston it will be seen that by the arrangement indicated it is easy to vary with precision the maximum power of the light power device within the widest limits, which is a great advantage.
 55 The apparatus being stopped under the action of the light power device, the governor assumes its lower position as also do the levers e and f. If the driver operates the axle S so as to raise the rod T with the 60 counterweight P the rod T will automatically hook itself to the knuckle lever U under the action of the spring within the rod V and at the same time the valve H will retake the position shown in the drawing Fig. 2 65 while the throttle valve O will be opened.

The steam being admitted under the piston E the light power device will be immediately released and the apparatus will be ready to move. If the driver puts his machine into action too sharply the governor l 70 rises immediately and presents the lever e in front of another step so as to bring about a fresh stoppage of the apparatus. If when the rising cage enters within the dangerous zone of the pit shaft the speed of the apparatus is slackened and if this slackening is effected continuously and suitably so as to bring the cage to the pit mouth level with a speed involving no danger, the governor descends and will gradually arrive at its lower 75 position while the lever will successively pass in front of all the steps without engaging them and the cage will arrive at the pit mouth without the light power device being operated.

I claim:—

1. The herein-described controller for hoisting apparatus comprising, in combination, a brake, a main power device, a connecting element associated operatively therewith, 90 an auxiliary power device connected to said element, automatic operating means for one of the power devices, and means whereby the auxiliary power device may operate the brake through said connecting element 95 either alone or in conjunction with the main power device.

2. The herein-described controller for hoisting apparatus comprising, in combination, a brake, a main power device, a balance 100 lever between said power device and the brake, an auxiliary power device connected to said lever, automatic operating means for one of the power devices, and means to apply power to said brake through said balance 105 lever either by one of said power devices acting alone or in conjunction with the other.

3. In hoisting apparatus, the combination with friction means, of a balance lever connected thereto, a main power device so associated with said lever as to operate the same in one direction, an auxiliary power device connected to said lever to hold the same in position to be engaged by the main power device or to operate the lever independently of the main power device and automatic operating means for one of the power devices. 110 115

4. In hoisting apparatus, the combination with a brake, a lever, and a main power 120 device associated therewith, of an auxiliary power device connected to said brake lever to operate the same independently or in conjunction with the main power device, automatic operating means for one of the power 125 devices, and a hand lever whereby the said power devices may be controlled.

5. In hoisting apparatus, the combination with a brake, a lever, and a main power device associated therewith, of an auxiliary 130

- power device connected to said brake lever to operate the same, automatic operating means for one of the power devices, and a hand lever movable a certain distance to 5 operate one of the power devices alone and subsequently movable in the same direction to bring into action the other power device.
6. In hoisting apparatus, the combination with a brake, a lever, and a main power device associated therewith, of an auxiliary power device connected to said brake lever to operate the same, hand means to control said power devices, and automatic means to cause operation of one of the said power 10 devices.
7. In hoisting apparatus, the combination with a brake, a lever, and a main power device associated therewith, of an auxiliary power device connected to said brake lever to 15 operate the same, means to control the operation of both of the power devices, and automatic means to cause operation of one of said power devices, said automatic means being variably operative in accordance with 20 variations in speed of the hoisting apparatus.
8. In hoisting apparatus, the combination with friction means, a main power device, and a connecting element between said power device and the friction means, of an auxiliary power device comprising a steam cylinder and piston connected to said connecting element to operate the same independently of the main power device, a plu- 25 rality of valves associated with said steam cylinder, hand means to operate one of said valves, and other means to operate the other of said valves.
9. In hoisting apparatus, the combination with friction means, a main power device, and a connecting element between said power device and the friction means, of an auxiliary power device comprising a steam cylinder and piston connected to said connecting element to operate the same independently of the main power device, a throttle, and automatic means connected with said cylinder to control the operation thereof and the throttle.
10. In hoisting apparatus, the combination with friction means, a main power device, and a connecting element between said power device and the friction means, of an auxiliary power device comprising a steam cylinder and piston connected to said connecting element to operate the same independently of the main power device, automatic operating means for one of the power devices, and an adjustable steam valve in direct connection with said steam cylinder to vary the effect thereof on the friction means.

In testimony whereof I have signed my name to this specification in the presence of two subscribing witnesses.

HUBERT JOSEPH DEBAUCHE.
